DEVICE FOR PEELING EGGS BY FLUID PRESSURE

John Bruce Richards, Indianapolis, Ind.

Application May 17, 1946, Serial No. 670,470

1 Claim. (Cl. 146—2)

1

This invention relates to means for removing the shells of hard boiled eggs. It has for a primary object the provision of means for quicker and complete separation of the shell from the egg together with the intervening membrane between the shell and the white of the egg. A further important object of the invention is to prevent damage or injury to the white of the egg during the shell removal operation. These and other objects and advantages of the invention will become apparent to those versed in the art in the following description of the invention, as illustrated in the accompanying drawing, in which

Fig. 1 is a view in side elevation and partial section of a structure embodying the invention;

Fig. 2, a view in end elevation;

Fig. 3, a view in top plan;

Fig. 4, a view in central vertical section through a modified form of the invention;

Fig. 5, a top plan view of the form shown in Fig. 4;

Fig. 6, a view in side elevation and partial section of a still further modified form; and

Fig. 7, a view in top plan of that form shown in Fig. 6.

Like characters of reference indicate like parts throughout the several views in the drawing.

Referring first to that form of the invention as illustrated in Figs. 1 to 3, an elastic cup 10 is mounted upon any suitable upright standard, herein shown as a short length of pipe 11. A collar 12 is first secured along the pipe 11 by any suitable means, such as by screw threads, and then a plate 13 has the upper end of the pipe 11 inserted through a hole therethrough to have the plate 13 rest on the collar 12. The floor of the cup 10 is perforated to receive the upper end of the pipe 11 therethrough and is brought down to rest against the top side of the plate 13. A washer 14 is placed around the upper end of the pipe 11 to rest on the top side of the floor of the cup 10 and then a nut 15 is screw-threadedly engaged around the upper end of the pipe 11 to clamp the floor of the cup 10 between the plate 13 and the washer 14. As indicated in the drawing, cup 10 preferably has an inturned lip 16 extending around its upper marginal portion to define an opening therethrough less than the major diameter of an egg. In fact, the diameter is made to be such that when the small end of the egg is inserted through the hole or top opening of the cup 10, the shell will come to rest around the marginal edge 16 to space the end of the

2

egg a slight distance above the nut 15 and the upper end of the pipe 11.

An arm 17 is carried outwardly and downwardly from the plate 13 to present a slightly arcuate surface, from which protrude top and bottom puncture pins 18 and 19, respectively. The lengths of these pins 18 and 19 are made to be such that when the small end of an egg is pressed thereagainst to come into contact with the outer surface of the arm 17 between those pins, the pins will enter through the shell of the egg and also the membrane thereunder, but will not penetrate the white of the egg any appreciable distance. In fact, such penetration is purposely kept down to a dimension on the order of hundredths of an inch so that when the egg is withdrawn from those pins, what little penetration has been had will be unobserved by reason of the fact that the white of the egg will close together about the cut, or cuts, made. The pins 18 and 19 are quite sharp, to facilitate penetration of the shell.

The lower end of the pipe 11 is connected to some suitable source of gas under pressure, such as a hand pump, an ordinary air compressor line, or with the usual carbonic acid gas tank. In the present showing, the pipe 11 is screw-threaded into a T fitting 20 from which a pipe 21 leads to the pressure source (not shown). Some type of valve to control the pressure in the pipe 11 is provided. In the present showing, Fig. 4, one type of valve suitable is indicated wherein there is a valve body 22 screw-threaded into one of the openings of the T 20 opposite the pipe 21. A valve 23 is maintained against a seat 24 by means of a valve rod 25 slidably extending through the body 22 to be connected with an outer button 26 normally urged to an outer position by means of a spring 27 between that button 26 and the body 22. The body 22 in the form indicated forms a gas tight seat at the shoulder 28 so that flow from the pipe 21 to the pipe 11 is had only when the button 26 is pushed to the right to move the valve 23 off its seat 24 to permit the flow to be had through the bore 29 and out through the lateral passageway 30 to the pipe 11.

In practice, an egg is pushed or tapped by its small end against the pins 18 and 19 and twisted slightly in order to provide at least one cut through the shell and the membrane. No cracks in the shell should extend from the small end above the egg shell ring of contact with the cup edge 16. Also, the egg is tapped on its larger end to crack the shell without rupturing the membrane, and without producing fractures

down the sides of the egg from the large end to the small end. Then the small end of the egg is pressed down into the cup 10 to have the shell rest against the marginal edge 16 with the punctured end within the cup 10. The button 26 is pushed inwardly slightly to admit the gas slowly, following which the button is pushed quickly to full valve opening, whereupon that pressure is transmitted between the membrane and the white of the egg, first to separate the membrane from the egg white and crack the shell, and then to literally blow the shell outwardly from the egg to effect a complete separation thereof. Of course, the shell is held normally within the hand of the operator. No small particles of the membrane and shell are left on the egg, and a complete, thorough separation is had.

The foregoing description relates to an apparatus useable where the pressure in the line 21 is relatively low, but where the pressure runs up to more than forty-five pounds or more per square inch, then the modification shown in Figs. 4 and 5 is preferably used. In this modification, a nut 35 is used in place of the nut 15. This nut 35 is in effect a cap having the top closure 36 with lateral openings 37 thereunder, herein shown as four in number. In this form, the flow of the gas is directed laterally initially so as to prevent a sudden impact of undue proportions on the end of the egg, which might tend to blow apart the white of the egg itself.

In using the form of the invention shown in Figs. 4 and 5, a plurality of shell puncture pins 38, herein shown as four in number, are provided to project upwardly from the top closure 36. These pins 38 compare in size to the pins 18 and 19 above mentioned. The spacing of these pins 38 from the inturned cup lip 16 is made to be such that normally the lower end of the egg projecting downwardly from the lip 16 does not come into contact with those pins. By pushing the egg downwardly to distort the cup 10 slightly, or at least the lip 16, the lower end of the egg is brought against these pins 38 and punctured thereby to provide the necessary opening through the shell and membrane for entrance of the flow of gas between the membrane and the white of the egg. Following the puncturing of the lower end of the egg, pressure on the egg may be relieved to where the egg would be returned to its upper normal position, sealing against flow of gas outwardly around the egg between the outside of the shell and the lip 16. In this form, of course, care must be exercised that the egg is not forced down too far against the resilient opposition of the cup 10, otherwise the lower end of the egg will be damaged beyond the mere cutting through of the shell and membrane to such an extent that the white of the egg will be broken to allow the flow of gas to enter interiorly.

Referring to that form of the invention as illustrated in Figures 6 and 7, means are provided to aid in securing just the right degree of pressure applied by the operator on the egg downwardly against the puncturing pins 38. In this form of the invention, the pins 38 are shown as being mounted upon a plain type of nut 15 and the pipe 21 is mounted to be connected to a relatively low pressure line, since the flow through the pipe 11 is unrestricted at the top end and the entire blast therefrom would be directed immediately against the lower end of the egg.

Referring to Fig. 6, a tubular sleeve 39 is provided to fit slidingly downwardly over the upper

end of the pipe 11. A spring 40 is carried within the sleeve 39 to bear against the upper end of the pipe 11 and an upper inturned end of the sleeve 39, whereby the sleeve 39 is normally positioned in an upper position. The floor 41 of the cup 10 has the sleeve 39 carried centrally downwardly therethrough, and a nut 42 screw-threadedly engages around the sleeve 39 to compress the marginal portion of the floor 41 around the sleeve against an outturned flange 43 provided on the sleeve 39 at its top end.

A short length of tube 44 is fixed to the pipe 11 and extends upwardly within the spring 40 to project normally above the upper flange end 43 of the sleeve 39. The nut 15 is screw-threadedly engaged around the upper end portion of this tube 44. A sealing gasket 45 is provided around the tube 44 to bear against the under side of the nut 15. The spring 40 normally pushes the upper end 43 of the tube 39 against this gasket 45 to provide a gas-seal therebetween.

In using this form of the invention as illustrated in Figs. 6 and 7, the small end of the egg is inserted into the cup 10 to have the egg bear against the lip 16, forming a seal therearound. The top end of the nut 15 and the supporting tube 44 are spaced below the lower end of the egg with the parts in the positions illustrated in Fig. 6. By pushing the egg downwardly slightly, the cup 10 bodily travels downwardly against the resistance of the spring 40 to allow the lower end of the egg to be brought against the pins 38 to perform the puncturing operation. Following the puncturing, the downward push on the egg is relieved sufficiently to permit the cup 10 to return to its normal upper position, whereupon the button 26 is momentarily pushed inwardly and then released to secure the quick impact of the gas flow against the lower punctured end of the egg, whereupon the shell is split open and separated from the white of the egg as above indicated.

While I have herein shown and described my invention in the best forms as now known to me, it is obvious that structural variations may be employed without departing from the spirit of the invention, and I therefore do not desire to be limited to those precise forms beyond the limitations as may be imposed by the following claim.

I claim:

In a device for removing the shell from a hard-boiled egg, an elastic cup having an opening less in diameter than the major transverse diameter of an egg; a pressure line centrally entering the floor of said cup; means for controlling flow through said line into said cup from zero pressure to full pressure in the line; and means for puncturing the small end of the egg to be entered through said cup opening, said means comprising at least one sharpened pin whose overall length is substantially limited to penetrating the egg shell and the membrane appearing between the shell and the egg white, whereby pressure created in said cup may be transmitted only exteriorly of said white and interiorly of said membrane; and a member relatively fixed within said cup upon which the pin is mounted to have the free end of the pin normally below the egg shell when the egg is inserted in said cup by its small end to contact the margin of said cup opening; means normally, resiliently maintaining said cup at the elevation withholding the egg's small end spaced from said pin, said last means permitting said cup to move bodily under sufficient pressure upon the egg placed in said cup opening to have the egg press against said pin for shell puncturing, the

travel of the egg being limited by the egg's contact with said pin carrying member; said pin carrying member being mounted on said pressure line; a sleeve carrying said cup and slidingly fitting said pressure line; and said cup resilient maintaining means consisting of a spring bearing between said sleeve and said pressure line; outer travel of said sleeve being limited by abutment with said pin carrying member; and a gasket between said last member and said sleeve for compression therebetween to form a gas tight joint therebetween when said cup is urged by said spring to said elevation.
